UNITED STATES PATENT OFFICE.

EMORY J. GREENE, OF PEORIA, ILLINOIS.

HEATING SYSTEM FOR BUILDINGS.

No. 807,819.

Specification of Letters Patent.

Patented Dec. 19, 1905.

Application filed September 22, 1902. Serial No. 124,272.

To all whom it may concern:

Be it known that I, EMORY J. GREENE, a citizen of the United States, residing at Peoria, in the county of Peoria and State of Illinois, have invented certain new and useful Improvements in Heating Systems for Buildings; and I do hereby declare that the following is a full, clear, and exact description of the invention, which will enable others skilled in the art to which it appertains to make and use the same.

This invention relates to heating buildings by steam or hot water, and particularly to novel devices employed in the apartments to be heated, the primary object being to secure effective and economical heating without encumbering the rooms with anything noticeable to the eye or occupying the ordinary space within the rooms. An ordinary radiator usually occupies space desirable for other purposes, is not ornamental, cannot be moved, and prevents proper removal of dirt and compels the mutilation of carpets. All these evils are avoided through the use of my invention, which provides for placing the heating devices in suitable recesses in the walls of the rooms and then allowing the air of the room to pass into such recesses below and back into the room above. In ordinary dwelling construction each apartment is provided with a base-board forming part of the wall, but standing out beyond the plane of the part above, and it is usually a simple matter to replace this by my devices in which heating-pipes are concealed behind a thin metal structure which has the appearance of the ordinary base-board.

In the accompanying drawings, Figure 1 is a sectional elevation of the wall of a room, showing my devices in position in the space usually occupied by a base-board. Fig. 2 is a front elevation of such a base-board, the concealed heating-pipes being indicated by dotted lines. Fig. 3 is a sectional plan view of a room having heating-pipes in the walls. Fig. 4 is a diagram showing a desirable arrangement of heating-pipes.

In Figs. 1 and 2, A represents the flooring of a room in a frame building; B, the studing; C, the lathing, and D the plaster thereon. At a suitable distance above the floor is a molding E, which may be the base-board molding ordinarily used. The base-board being absent and the lath and plaster being omitted below the molding, there is left a re-

cess, and this is lined above, below, and in the rear or next the studs or body of the wall with a sheet F of asbestos or the like incombustible non-conductor, and over this is placed a second lining G of sheet metal. In the recess thus lined is placed a vertical series of heating-pipes H for carrying steam or hot water. In front of these pipes is placed a metal sheet I, simulating the ordinary base-board, having its upper marginal portion bent inward a little below the molding E and provided near the floor with slightly-separated apertures. The pipes are supported in this space in any suitable way at some distance from each of the four walls of the recess behind the plate I and the plate is secured by screws K M to studs J and blocks L or in any manner permitting ready detachment. The visible portions, such as the molding E and plate I, are preferably painted or finished to correspond with the finishing of the room.

Fig. 3 shows a steam-supply pipe N, from which steam passes through pipes O Q to heating-pipes P R, respectively, in the wall. Return-pipes S and T and a common pipe U lead back to the source of supply. (Not shown.)

Fig. 4 merely illustrates connecting each of a series of heating-pipes to common supply and return pipes. It is, however, to be understood that the arrangement of pipes and details of construction may be varied in various ways and that the heating-pipes may be placed in any or all the walls of a room. The number of pipes in each bank will naturally be varied with the heat required or as the conditions in the particular case may suggest.

What I claim is—

1. The combination with a wall having a projection along the line usually occupied by the upper side of a base-board, of heating-pipes located near said wall below said projection, and a plate secured in front of said pipes below said projection and adapted to permit air to pass to and from the pipes near the lower and upper sides of the recess in which they lie.

2. The combination with a wall having a projection along the line usually occupied by the upper side of a base-board, of heating-pipes located near said wall below said projection, and a plate fixed below said projection at a short distance in front of said pipes

and adapted to allow air to pass to and from the pipes near the lower and upper sides of the recess in which they lie.

3. The combination with a wall having a projection along the line usually occupied by the upper side of a base-board, of heating-pipes located near the wall below said projection, and a removable plate located below said projection a little in front of the pipes, having its upper portion bent inward, and adapted to permit air to pass to and from the pipes near the lower and upper sides of the recess in which they lie, and a series of plate-upports located in said recess.

4. In heating devices, the combination with a wall having a recess in the place of the usual base-board, of a non-conducting lining for the top, bottom and rear walls of the recess, a metal lining protecting the non-conducting lining, a molding extending along the wall just above the recess, heating-pipes supported in the recess out of contact with its walls and with each other, a metal plate forming the front wall of the recess, having

its upper edge bent rearward below said ²⁵ molding, and closing the recess except near its top and bottom, and screws detachably fixing the plate in position.

5. In apparatus for heating a room, the combination with side walls having along the ³⁰ floor a recess having the height of an ordinary base-board and extending inward to the studding of the wall, of a thin lining for the recess, a thin vertical plate lying in the plane usually occupied by the face of the base-board and arranged for the entrance of air below and its exit above, and a series of heating-pipes in the same vertical plane, of a diameter less than the distance between the plate and lining, and fixed midway between ³⁵ ⁴⁰ said plate and lining.

In testimony whereof I affix my signature in presence of two witnesses.

EMORY J. GREENE.
